UNITED STATES PATENT OFFICE.

WILLIAM F. REGAN, OF NEW YORK, N. Y., ASSIGNOR TO UNIVERSAL PAPER BOTTLE CO., OF WILMINGTON, DELAWARE, A CORPORATION OF DELAWARE.

METHOD OF MAKING PAPER BOTTLES.

1,187,388.

Specification of Letters Patent. Patented June 13, 1916.

Application filed November 19, 1913, Serial No. 801,822. Renewed September 11, 1915. Serial No. 50,264.

To all whom it may concern:

Be it known that I, WILLIAM F. REGAN, a citizen of the United States, residing at the city of New York, borough of Brooklyn, county of Kings, and State of New York, have invented a certain new and useful 5 Method of Making Paper Bottles of which the following is a specification.

This invention is a method of making containers from fibrous materials, such as shaped paper bottles, whereby an article with a closed bottom and a tapering neck portion may be manufactured rapidly and economically.

According to the preferred mode of procedure in producing the container, a prepared bottom member is positioned in coöperative relation to a forming mandrel, and the fibrous material required to form the 10 body of the container is fed or supplied to said forming mandrel, whereupon the mandrel and the prepared bottom are rotated, as a result of which the paper is wrapped or coiled upon the mandrel and around the 15 bottom. The next step is to infold the material with respect to the bottom, and to unite the bottom and the cylindrical material at one end portion of the latter, thus resulting in an embryo container consisting 20 of a cylindrical body and a bottom closure united thereto. Such embryo container is now, preferably, transferred to a forming mandrel, the latter coöperating with suitable mechanism which imparts a taper to an 25 end portion of the cylindrical body so as to produce a desired taper thereon. The material of the cylindrical body is crimped for producing the tapering neck on the container, and for confining the crimped material 30 in place so as to overcome any disarrangement of the crimps, particularly at the neck of the bottle, a band is applied exteriorly to the crimped material, preferably by winding or coiling a strip or web of material around the crimps at the neck adjacent 35 to the mouth or outlet of the bottle.

The container produced according to the specified procedure is characterized by several features of novelty as follows:—First, 40 the crimps in the neck portion extend lengthwise of the container, they are tapering so as to increase in depth from the cylindrical body toward the mouth, and the crimped material results in ribs the material 45 of which is within the chamber of the neck

or body, thus leaving the external surface of the container comparatively smooth and free from projections; second, the crimped material at the neck is bound or confined firmly in place by the neck band so as to 50 result in a structure the crimped part of which is retained permanently in predetermined relation so as to preclude any breaking down of the mouth portion and which mouth portion presents a smooth external 55 surface adapted for the reception of a suitable cap or closure, and, third, the bottom and the cylindrical body are permanently united in a way to protect and reinforce the bottom by the material of the container and to secure a liquid tight joint between said 60 bottom and the container.

Other features and advantages of the invention will appear from the following detailed description.

In the drawings, Figure 1 is a plan view, partly in section, illustrating the first step in the formation of the container which consists in positioning a closure in operative 70 relation to an end face of a forming mandrel. Figs. 2 and 3 are plan and side views illustrating the second step in the formation of the container which consists in wrapping a length of paper around the forming mandrel and the closure positioned against the 75 end face of said forming mandrel. Fig. 4 is a sectional plan view illustrating the third step which consists in uniting an end portion of the container body to a closure for 80 said container body. Fig. 5 is a plan view, partly in section, illustrating the parts preliminary to the fourth step which consists in crimping a portion of the cylindrical container body so as to produce a tapering neck 85 thereon. Figs. 6 and 7 are views in plan and end elevation, respectively, illustrating the fifth step which consists in winding a neck band around the crimped neck portion 90 of the container body. Fig. 8 is a side elevation of a complete container embodying 95 the invention. Fig. 9 is a plan view of the container shown in Fig. 8. Fig. 10 is a horizontal section on the line 10—10 of Fig. 8.

In carrying the invention into practice, I employ a rotatable forming mandrel A to 105 which is fed the material adapted to form the body and the closure for one end of said body, thus resulting in a container, the body and closure of which are united so as to result in a unitary structure. The first step 110

consists in positioning the closure against the end face of the cylindrical forming mandrel A, said closure being illustrated in the form of a disk B having a flange b. The closure forms the bottom of the container, for which purpose the diameter of the closure is equal to the internal diameter of the container, and in presenting the closure to the end of the forming mandrel the flange b of said closure disk is substantially flush with the cylindrical surface of the forming mandrel. The closure having been positioned with respect to the mandrel as described, I next proceed to form the container body, for which purpose a length of paper C is supplied to the mandrel, whereupon said mandrel is rotated so as to wrap or coil the paper C upon the mandrel and the flange of the closure. The paper or other fibrous material may be supplied from a web or in sheets, it being preferred to feed the sheets successively to the forming mandrel. The paper is coated with an adhesive substance along one side margin, as at c, and one edge margin, as at c'. This coating may be supplied to the paper and dried thereon in the operation of preparing the paper for use in the machine, or, if desired, the adhesive coating at c c' may be supplied in a wet condition and by suitable devices during the operation of feeding the paper to the forming mandrel. When prepared sheets of paper with dried adhesive coatings thereon are applied it becomes necessary to moisten the adhesive coatings before or during the operation of feeding the sheet to the forming mandrel, and when the paper is coiled upon the mandrel the convolutions of the paper will adhere to each other, the innermost layer of paper adhering to the flange b of the closure. Having wrapped the paper C around the mandrel and the closure, as illustrated in Figs. 2 and 3, the next step is to infold a protruding portion of the paper around the gummed margin c thereof into contact with the inner surface of the flange b of the closure, substantially as shown in Fig. 4. This is performed by suitable mechanism during the rotation of the mandrel, said mechanism being in the form of a bending roll having one or more flanges operating on the material to press the gummed margin c into contact with the inner surface of flange b, whereby the paper composing the body of the container is united to the flange b of closure B both exteriorly and interiorly of said flange.

Subsequent to the operation of forming the material into a cylindrical body and uniting the end closure to said cylindrical body the embryo container is transferred from forming mandrel A to a crimping mandrel D, illustrated more particularly in Figs. 5 and 6. The embryo container is transferred by any suitable means from

mandrel A to mandrel D so as to assume the position upon the latter illustrated in Fig. 5, and the material at the open end of the container is manipulated by suitable mechanism disclosed in a co-pending application Serial No. 801,820, filed even date herewith, for the purpose of crimping the material, thus resulting in a tapering neck at an end portion of the container. As shown, the crimping mandrel D is tapering at one end, as at d, and is provided with a series of longitudinal slots d'. With this mandrel cooperates a series of exteriorly positioned crimping fingers which act upon the cylindrical end portion of the container body so as to force the material into the slots d', thereby producing a series of ribs e on the container body. The folds of the material constituting the ribs e are positioned interiorly of the container, and they extend from the cylindrical part of the container body to the neck portion thereof. The material is crimped so as to impart the desired taper to the container, and this material at one end thereof is formed around a collar D' of the crimping mandrel, so as to produce a substantially cylindrical mouth portion at the end of the tapering bottle neck. Obviously, the crimped material will not retain its shape unless means are provided for binding the crimped material firmly in position, and to this end a neck band is applied exteriorly to the crimped material. It is preferred to feed a length or strip of narrow paper E to the mouth portion of the container, and to wind this strip or length of material exteriorly upon the crimped material at said mouth portion, thereby producing a neck band which is firmly united to the crimped material so as to produce a smooth external surface and to retain the crimped material in a firm position. The neck band should, of course, be coated with adhesive material, as at e', in order that it may be united to the crimped material of the bottle. Obviously, the mandrel is rotated and the neck band material is fed to the crimped material of the container, whereby the neck band may be applied expeditiously and accurately to the paper bottle. Subsequent to the application of the neck band, mandrel D is collapsed in order to withdraw it from contact with the container, and the latter is ejected by suitable mechanism from the mandrel while the latter is in a collapsed state.

The procedure herein described results in a container, illustrated more particularly in Figs. 8, 9 and 10 of the drawings, the bottom of said container being closed by the flanged disk B which is united firmly to the material of the body so as to secure a liquid-tight joint therewith. The container F consists of a cylindrical body, the neck portion of which is tapered by crimping the material

so as to produce the webs *e*, the latter being in the form of ribs positioned interiorly of the bottle. The webs or ribs *e* extend lengthwise of the tapering neck portion of the bottle and they increase in depth from the cylindrical part of the body to the mouth portion of the bottle, the material of the crimps at one end thereof being pressed firmly upon the collar *D'* of the forming 5 mandrel so that these compressed portions of the crimped material constituting the mouth of the bottle will be united firmly together by the neck band *E'*, the latter being formed by winding the length of paper 10 *E* around the crimped material next to the mouth of the bottle.

It is evident that the bottle may be produced rapidly and economically, for the reason that the several operations are performed by automatic machinery.

Subsequent to the completion of the bottle or other container, it is manipulated or treated to render it waterproof, such, for example, as by coating the bottle either interiorly or exteriorly, or both, with paraffin or other agents.

Having thus fully described, the invention, what I claim as new, and desire to secure by Letters Patent is:

30 1. The method of making paper bottles which consists in positioning a flanged bottom member into contact with a solid end face of a rotatable non-collapsible forming mandrel, feeding a web of paper to said 35 mandrel, rotating the mandrel and the bottom member simultaneously to wind the paper web upon the mandrel and the flange of the bottom member, infolding the coiled web interiorly of the flange on said bottom 40 member, removing the resulting embryo bottle from the forming mandrel, positioning said embryo container upon a collapsible crimp-forming mandrel, producing crimps in the embryo container and imparting a 45 taper to the bottle, and subsequently winding a narrow band around the crimped mouth portion of the bottle.

2. The method of making paper bottles which consists in winding a web of paper 50 upon a rigid non-collapsible forming mandrel and simultaneously attaching a bottom closure to an end portion of the coiled web

so as to produce on said forming mandrel an embryo bottle, then removing the embryo bottle from said forming mandrel, then inserting a collapsible crimping mandrel into the open end of the embryo paper bottle, then producing longitudinal tapering crimps in the coiled material, then compacting said crimped material at the open end of 55 the embryo bottle and winding exteriorly thereon a narrow band, and finally ejecting the completed bottle from said crimping material.

3. The method of producing shaped containers from fibrous material which consists in winding a web of paper upon a forming mandrel and at the same time uniting an end closure to the resulting container body, removing the embryo container from the forming mandrel and positioning the same upon a crimping mandrel, crimping the material for definite distances lengthwise of the embryo container while present upon the crimping mandrel so as to impart a taper 70 to the neck portion of the container, and binding the crimped material by applying a binder externally to the mouth portion of said container.

4. The method of producing shaped containers from fibrous materials which consists in winding a web of paper upon a forming mandrel and at the same time uniting a closure to an end portion of the resulting container body, removing the embryo container 85 from the forming mandrel and positioning the same upon a crimping mandrel, crimping the material of the container body and imparting a taper to the neck portion thereof by folding said material on predetermined 90 lines and lengthwise of said body so as to produce ribs which increase in depth toward the mouth of the container and are positioned inwardly with respect to said container, and applying a binder externally to 95 the crimped material at the mouth portion of the container.

In testimony whereof I have signed my name to this specification in the presence of two subscribing witnesses.
